CONTROL APPARATUS FOR OIL BURNERS

Kenneth French, Waterbury, Conn.

Application May 2, 1940, Serial No. 332,999

1 Claim. (Cl. 158—28)

This invention relates to oil burner controls, and more particularly to an improved apparatus for automatically controlling the flow of oil from a supply tank to an oil burner.

The control apparatus of this invention is primarily designed for use with oil burners of the type wherein a pilot light is kept burning continuously, but it may also be advantageously used in those types of oil burners normally operating under "low fire" with intermittent need for a "high fire."

One object of this invention is to provide an improved control apparatus of the above nature having a manually adjustable valve to maintain the desired "low fire" and a thermostatically and electromagnetically controlled main valve for producing the operation of the "high fire" when needed.

A still further object of this invention is to provide an improved control apparatus for oil burners of the above nature which will be relatively inexpensive to manufacture, simple in construction, compact, ornamental in appearance, and very efficient and durable in use.

With these and other objects in view, which will appear as the description proceeds, there has been illustrated in the accompanying drawing one form in which the invention may be conveniently embodied in practice.

In the drawing:

Fig. 1 is a schematic layout of an oil burner system showing the disposition of the control apparatus of this invention in relation to an oil burner and a source of fuel supply.

Fig. 2 is a top plan view of the improved control apparatus with the protecting cover shown in section.

Fig. 3 is a sectional view of the same taken on the line 3—3 of Fig. 2.

Fig. 4 is a sectional view taken on the line 4—4 of Fig. 3.

Referring now to the drawing wherein like reference numerals designate corresponding parts throughout the several views, the numeral 10 denotes a tank containing a supply of oil or other liquid fuel, 11 an oil burner mechanism, and 12 a normally open thermostatically-actuated electric switch, all of which may be of any well-known standard constructions. Instead of connecting the supply tank 10 directly to the oil burner mechanism 11 as is usual in oil burner installations, an intermediate fuel reservoir 17 is located therebetween, said reservoir 17 being connected to said tank 10 by a pipe 13. The switch 12 is electrically connected to a line wire

L' by a conductor 15, and the burner 11 is connected to a line wire L² by a conductor 16. Any suitable standard mechanism (not shown) may be employed to maintain the fuel level in the reservoir 17 at a point above the inlets to the needle valves.

The fuel reservoir 17 has a threaded fuel inlet connector 18 upon which a threaded collar on the end of the pipe 13 is adapted to be screwed, 10 and an outlet 19 is provided which is connected to the oil burner valves by a pipe 20. The reservoir 17 is shown mounted on a vertical standard 21 so that the reservoir may be elevated above the burner 11. A low fire or pilot control valve 15 23 is disposed in the reservoir 17 below the fuel level 22, and includes a valve seat 24 disposed between an inlet port 25 covered by a screen 26 and an outlet port 27. A needle valve stem 28, screw threaded into a boss 29 extending upwardly 20 from the valve 23, passes through a stuffing box 30 and then upwardly through a flat cover 31 provided for the reservoir 17. Above the cover 31 the valve stem 28 has a thumb knob 32 secured thereto, upon which is provided a pointer 33 25 adapted to be moved over a circular dial 34 provided on the cover 31 to visually indicate the position of the valve 23.

The outlet port 27 of the valve 23 is connected through an integral tubular portion 35 to an outlet port 36, provided in a vertical valve body 37, and which is in connection with the reservoir outlet 19. The tubular portion 35, in this instance, is shown screw threaded, as at 38, into the valve body 37, and the latter extends from the cover 31 to the bottom 39 of the reservoir, and is secured to each by nuts 40 and 41 respectively screwed upon upper and lower screw threaded ends 42 and 43 of the valve body 37. The valve body 37 is counter-bored downwardly from its upper end 42, and in this bore 44 a needle valve stem 45 is adapted to slide. The bore 44 is connected with the outlet port 36 through a port 46, and with the fuel supply, below its level 22 in the reservoir 17, by an inlet port 47 which is also covered by a screen 48.

The valve stem 45 has an enlarged portion 49 which fits in the bore 44 and has the lower end of a coiled spring 50 seated against its upper end. The spring 50 is arranged to constantly react between the enlarged portion 49 of the stem 45 and the nut 40 to normally hold the valve stem 45 in valve closing position in the port 46. The valve stem 45 has an extension 51 above the enlarged portion 49, which passes upwardly through the nut 40 and is connected to one end of a first-

class lever 52 by a short link 53. The lever 52 is pivoted at 54 to a vertical post 55 secured to the cover 31 by a screw 56. The other end of the lever 52 is pivotally connected loosely to a core member 57 which is adapted to freely move up and down in the bore 58 of a cylindrical solenoid 59. The solenoid 59 is secured to the cover 31 by a band 60 and screws or rivets 61. Electrical conductors 62 and 63 are flexibly connected with the solenoid 59 and lead to the thermostatically controlled switch 12, through the conductor 14, to the line wire L², and through the conductor 16, respectively, whereby the solenoid 59 will be energized when the thermostatic switch 12 is closed. A protecting cover 64 removably hinged at 65 to the cover 31 is provided with a catch finger 66 adapted to engage in a slot 67 in the cover 31.

Operation

After the burner is lighted, the valve 23 will be manually set to maintain the desired degree of "low fire," or to maintain a pilot flame of the proper size. When the thermostatically controlled switch 12 is actuated by the lowering of the room temperature, the solenoid 59 will be energized to attract the core member 57 downwardly. Movement of the core member 57 downwardly into the solenoid bore 58 tilts the lever 52 about its pivot 54, and through the link 53, and the stem extension 51 raises the needle valve stem 45 to open the port 46 and allow fuel to flow from the reservoir to the burner mechanism 11 through the outlet 19 to provide a "high fire."

The provision of a reservoir in which the inlets of both of the above control valves are disposed above the bottom of the reservoir insures that only clean oil is delivered to the burner mechanism 11, as no sediment can enter the inlet ports 25 and 47, nor clog up the screens 26 and 48.

It will be understood that the valves of the oil burner 11 will be initially set for the most efficient flame, and will need no further adjustment. The present invention thus acts as a safety mechanism by eliminating the manual control of the burner valves.

It will be understood that the present invention may be installed on an oil burner of any type already in use or newly constructed. In the latter case, the reservoir will preferably be made as an integral part of the usual reservoir provided therein.

While there has been disclosed in this specification one form in which the invention may be embodied, it is to be understood that this form is shown for the purpose of illustration only, and that the invention is not to be limited to the specific disclosure, but may be modified and embodied in various other forms without departing from its spirit. In short, the invention includes all the modifications and embodiments coming within the scope of the following claim.

Having thus fully described the invention, what is claimed as new and for which it is desired to secure Letters Patent, is:

20 In an oil burner control apparatus, a housing containing oil, said housing having an inlet for connection to a source of oil supply and an outlet for connection to an oil burner, a vertical valve chamber in said housing directly above and connected with said outlet, a main valve seat in said vertical valve chamber, a normally closed main valve for engaging said main valve seat, a side chamber connected to said vertical chamber below said main valve seat, said side chamber having a vertical upstanding section, a pilot valve seat in said side chamber, a pilot valve in said upstanding section for engaging said pilot valve seat, said vertical chamber having an inlet opening below the oil surface and above said main valve seat, said side chamber having an inlet opening below said pilot valve seat, said main valve having a stem extending above the top of said housing for connection to a thermostatically operated mechanism to automatically open said valve when high heat is called for, said pilot valve also having a stem extending above the top of said housing, and having a manually-operated control handle connected thereto.

KENNETH FRENCH.
